UNITED STATES PATENT OFFICE.

DWIGHT T. ROGERS, OF MACHIAS, NEW YORK.

MILKING-STOOL.

1,295,927.

Specification of Letters Patent.

Patented Mar. 4, 1919.

Application filed June 2, 1917. Serial No. 172,365.

To all whom it may concern:

Be it known that I, DWIGHT T. ROGERS, a citizen of the United States, residing at Machias, in the county of Cattaraugus and 5 State of New York, have invented certain new and useful Improvements in Milking-Stools, of which the following is a specification, reference being had therein to the accompanying drawing.

10 My invention relates to milking stools and has for its purpose to provide an improved construction whereby the pail supporting elements can be adjusted to different angular relations with respect to the seat element 15 of the stool, such adjustments being effected with ease and facility and through the medium of an exceedingly simple and inexpensive structure.

20 Furthermore it is my purpose to provide a pail supporting element in the form of a ring which can also be adjusted, when not in use, to a position surrounding the seat element of the stool and in substantially the same plane as the seat element.

25 With the above and other purposes in view my invention consists in the details of construction and in the arrangement and combination of parts to be hereinafter more fully described and particularly pointed out 30 in the appended claims.

35 In describing my invention in detail reference will be had to the accompanying drawings wherein like characters of reference denote corresponding parts in the several views, and in which—

Figure 1 is a side elevation of my improved milking stool partly broken away and showing various adjustments of the pail supporting ring in dotted lines;

40 Fig. 2 is a plan view of what is shown in Fig. 1;

Fig. 3 a partial vertical section of what is shown in Fig. 1, and

45 Fig. 4 is a detail perspective view of a fragment of the pail supporting ring.

Referring to the drawings, my improved milking stool is shown as comprising a base 10 in the form of an upwardly tapering hollow metallic pedestal. It will be understood 50 however that this base can be of any desired construction and formed of any desired material. Revolubly mounted on the upper end of the base 10 concentric with the latter is a seat 11 having a depending flange 12. Se- 55 cured to this flange 12 are the forked portions 13 of a radial arm 14. This arm is

provided with an inclined slot 15, and inwardly of said slot is an adjusting pin 16 for a purpose that will presently appear.

My invention further contemplates a pail 60 holding ring 17 having outwardly extending terminals 18 disposed in embracing relation to the arm 14. These terminals 18 carry intermediate their ends a pivot bolt 19 which passes through the inclined slot 15 and 65 whereby pivotal connection is afforded between the ring 17 and the arm 14. The terminals 18 are provided respectively with stepped notches 20 in which the pin 16 is adapted to selectively seat to hold the ring 70 17 in different angular adjustments with respect to the seat 11, as will be obvious, the pivot bolt 19 adapted to be moved back and forth within the inclined slot 15 to permit of such adjustment. The terminals 75 18 of the ring 17 are held in proper spaced relation by a brace plate 21 secured to the body of the ring at the inner ends of the terminals. In addition to the plate 21 serving the function of securing the terminals 18 in 80 proper relation it also acts as a stop for engagement with the arm 14 when the ring is swung into encircling relation with respect to the seat 11. This engagement of the plate 21 with the arm 14 occurs when the ring 17 85 is disposed substantially in the plane of the seat 11.

It will be noted that by revolubly mounting the seat and securing the supporting ring 17 thereto the pail can respond to any 90 forward or backward movement of the animal during milking without changing the position of the seat and base.

While I have illustrated and described one 95 form of carrying my invention into practice it will be obvious that various changes in the details of construction and in the arrangement of parts can be resorted to without departing from the scope of the invention as set forth in the appended claims. 100

What I claim is:

1. A milking stool comprising a base, a seat revolubly mounted on the base, a pail supporting member pivotally connected with the seat, and means for positively holding 105 said member in different angular adjustments with respect to the seat.

2. A milking stool comprising a base, a seat revolubly mounted on the base, a radial arm carried by the seat, a pail supporting 110 ring pivotally connected to the arm, and means carried by the ring and arm for se-

lectively holding the ring in different angular adjustments with respect to the seat.

3. A milking stool comprising a base, a seat revolvably mounted on the base, a radial arm carried by the seat and provided with an inclined slot, a pail holding ring having its terminals disposed in embracing relation to the arm, a pivot stud carried by said terminal portions and extending through 10 said slot, and a pin carried by the arm adapted to seat in stepped notches formed in the terminals of the ring to hold the latter in different angular adjustments with respect to the seat.
- 15 4. A milking stool comprising a base, a seat revolvably mounted on the base, a radial arm carried by the seat, a pail holding ring having its terminals disposed in embracing relation to the arm and pivotally connected thereto, and a brace plate connecting the ter-

25 minal portions of the ring and engageable with the arm to limit the pivotal movement of the ring in one direction.

5. A milking stool comprising a base, a seat mounted on the base, a radial arm carried by the seat, a pail supporting ring pivotally connected to the arm, and means carried by one of the last two mentioned members having stepped notches formed therein for engagement with a pin carried by the 30 other of said members, for the purpose of selectively holding the ring in different angular adjustments with respect to the seat.

In testimony whereof I affix my signature in presence of two witnesses.

DWIGHT T. ROGERS.
